REGENERATIVE PURGING SYSTEM FOR REFRIGERATING PLANTS

Filed Feb. 17, 1926

Patented Feb. 15, 1927.

1,617,631

UNITED STATES PATENT OFFICE.

NORMAN H. GAY, OF LOS ANGELES, CALIFORNIA.

REGENERATIVE PURGING SYSTEM FOR REFRIGERATING PLANTS.

Application filed February 17, 1926. Serial No. 88,824.

This invention relates to improvements in refrigerating plants and more particularly to purging systems for the same.

One object of this invention is to provide

5 a means for separating foreign gases and oil from the refrigerant circuit and to separate these undesired substances from the refrigerant medium in substantial freedom therefrom, whereby such substances may be with-
10 drawn without loss of refrigerant medium.

Another object is to accomplish this separation without the use of external heat and cold or the diversion of a part of the liquid refrigerant for the purpose, and by the mu-
15 tual and regenerative action of the two sub-
stances one upon another to separate the re-
frigerant therefrom.

Further objects will appear in the course of
the following specification, taken in conjunc-
20 tion with the accompanying drawing which
represents a diagrammatical layout of a re-
frigerating plant embodying the present re-
generative purging system.

In this plant, the usual compressor 10 de-
25 liveres the warm compressed gas through a
discharge valve 11 and the discharge line 12
to a high pressure oil trap 13, whence the gas
flows through the discharge pipe 14 to the
inlet header or manifold 15 of the condenser
30 16. The flow of gas to the condenser is regu-
lated by a condenser inlet valve 17. The con-
denser 16 may be of any appropriate design
and usually comprises a number of pipes
through which the gas may flow and which
35 are externally cooled by any suitable medium
such as water, so that the refrigerant gas is
condensed and liquefied therein and deliv-
ered in such condition to the outlet manifold
or header 18, whence it flows through a li-
40 quid valve 19 and the gravity liquid line 20
into the liquid receiver 21. The liquid re-
frigerant collects in the bottom of this re-
ceiver and is drawn off therefrom through
the liquid line 22 which is regulated by a
45 king valve 23, and passes to the liquid line 24
and through a liquid-stop valve 25 into the
liquid cooling coil 26 and thence through the
liquid line 27 and the expansion valve 28
to the gas separating chamber 29. The li-
50 quid-drop leg 30 from this chamber 29 leads
to a low pressure oil trap 31, from which
the refrigerant may flow through a pipe 32
and the liquid valve 33 into the liquid header
34 and thence into the refrigerating coil 35
55 which constitutes the means of cooling the ice
freezing tank, ice box or other chamber to

be chilled. The gases after having passed
through the coils 35 are collected in the gas
header 36 and pass thence through the suc-
tion valve 37 and suction riser pipe 38 to the
60 liquid separating chamber 39 and flow over
the surface of the liquid cooling coil 26, and
finally return through the main suction line
40 and its suction-stop valves 41 and 42 to
the compressor 10. This constitutes the nor-
65 mal circuit of the refrigerant medium
through the plant.

The gas separating chamber 29 and the
liquid separating chamber 39 are in free
70 communication with each other, so that the
gases separated in chamber 29 pass upward
into chamber 39, and the liquids separated
in chamber 39 pass downward into the cham-
ber 29.

It is necessary to employ lubricating oil
75 within the compressor 10 and it has been
found by experience that a considerable por-
tion of this oil is carried along with the out-
going warm gases through the discharge
valve 11 and pipe 12. A portion of this oil
80 is separated in the high pressure oil trap 13
and collects in the bottom thereof. This
trap 13 is exposed to the atmosphere and
is cooled thereby. The separated oil drains
85 into the high pressure oil line 43 and may
be relieved through the manually operated
valve 44 into the oil bus line 45 and thence
through the oil feeding valve 45^a into the
regenerator casing 46. The oil in passing
90 the valve 44 loses its high pressure and is
reduced to the low pressure prevailing in the
oil bus line 45; during which reduction, the
refrigerant contained therein is partly given
off and cools the oil.

A further portion of the oil is carried
95 along into the condenser 16, and trickles
downward through its pipes and the header
18 and along the pipe 20 until it is received
in the liquid receiver 21. Since the specific
gravity of this oil is greater than the spe-
100 cific gravity of the liquefied refrigerant me-
dium, the oil will pass to the bottom of the
receiver and flow therealong until it is
stopped by the dam or baffle 47 arranged
near one end of the receiver 21, in front of
105 the inlet to the liquid line 22. The oil ac-
cumulating in the receiver 21 drains into
the oil separator drum 48 and may be re-
lieved therefrom through the oil purging
valve 49 which leads to the cold oil pipe 50
110 which opens into the oil bus line 45 and
hence to the regenerator casing 46. The oil

in passing the valve 49 loses its high pressure and is reduced to the low pressure prevailing in the oil bus line 45; during which reduction, the liquid refrigerant contained 5 therein is partly given off and cools the oil. Any remaining oil carried along with the refrigerant medium enters the gas separating chamber 29 and passes downward through the pipe 30 into the low pressure oil 10 trap 31 which is preferably heat-insulated. Oil carried through the valve 33 into the chilling coil 35 and held within this coil will establish a reflux into the liquid header 34 when the system is shut down at any 15 interval, and thence flow back into the bottom of the low pressure oil trap 31 which serves as a drain, from which the oil may be relieved through the low pressure trap purging valve 51 into the oil bus line 45 and 20 thence into the regenerator casing 46.

Any foreign gases such as air or the like which may be contained within the system and which are not condensed at the temperature of the condenser 16 pass along and, 25 mingled with varying proportions of the refrigerant gas, accumulate in the outlet header 18; the foreign gases which are lighter than the refrigerant gas, accumulate in the upper portion thereof, from which they may 30 be drawn off with admixed refrigerant medium through the equalizing line valve 52 into the gas purging or equalizing line 53 which opens into the regenerator condensing coil 54 which is contained within the 35 regenerator casing 46. The foreign gases which are heavier than the refrigerant gas accumulate in the lower portion of the outlet header 18, from which they automatically 40 pass downward through liquid valve 19 and gravity liquid line 20 into the upper part of liquid receiver 21; from which they are drawn through valve 55 into coil 54. It will be noted that by manually manipulating valves 52 and 55 either the lighter 45 foreign gas may be taken from the top of the outlet header, or the heavier foreign gas may be taken from the top of the receiver at the option of the operator. The mingled foreign gases from the receptacles 18 and 50 21 are at a relatively high pressure and temperature but still contain gaseous refrigerant mixed therewith.

The regenerator coil 54 is optionally in communication through valve 55 with the 55 liquid receiver 21, so that liquid refrigerant forming in coil 54 can be withdrawn by gravity into receiver 21 and is thus reclaimed. The upper end of the coil 54 is connected through a foul gas purging valve 60 55 with a foul gas purging vent pipe 56.

The mingled oil from the receptacles 13, 48 and 31 is at a relatively low pressure and temperature, but still contains liquid refrigerant mixed therewith.

65 The regenerator casing 46 is in commun-

cation through a regenerator suction valve 57 and the regenerator suction line 58 with the suction line 40 of the refrigerating plant, so that any gaseous refrigerant forming in the regenerator casing will pass back into 70 the refrigerating system and thus be reclaimed. The lower part of the regenerator casing 46 is in communication through the oil purging valve 59 and the pipe 60 with a portable oil receptacle (not illustrated). 75

It will be noted that liquid refrigerant may be likewise drawn off through a valve 61 and pipe 62 for any other use, and it will be understood that the expanded refrigerant when so used will be returned into the 80 common suction line 40.

The method of operation of this system is as follows:

The refrigerant medium in gaseous form is withdrawn from the suction line 40 by 85 the compressor 10 and delivered in warm compressed condition through the pipe 12, high pressure oil trap 13, pipe 14 to the condenser 16, where it is in part liquefied, and the noncondensable foreign gases are 90 separated in the header 18 as set forth above and contain a varying quantity of the refrigerant medium in gaseous form, and may flow through the equalizing line 53 or through receiver and connection 55 to the 95 regenerator condensing coil 54. The liquid refrigerant mingled with oil passes into the receiver, and the oil is partly separated as described above, but always contains a 100 quantity of liquid refrigerant. Likewise, the oil separated in the low pressure trap 31 will contain a quantity of refrigerant 105 therein. The mixed oil and refrigerant is withdrawn from the several traps through their respective valves into the oil bus line 45 and thence into the regenerator casing 46 through the valve 45. Since the oil entering the casing is mingled with liquid refrigerant irrespective of whether it comes from the high pressure oil trap 13, the receiver oil trap 48, or the low pressure oil trap 31, the oil will give off this refrigerant in the form of a gas by evaporation of same under the low pressures prevailing, and the evaporation of this liquid refrigerant will cool 110 the oil to the temperature at which the refrigerant is evaporating, which will be considerably lower than the condensing temperature of the gaseous refrigerant under the pressure prevailing in the coil 54. This 115 gasifying refrigerant from the oil returns through the pipe 58 when the valve 57 is open into the return pipe 40. Since the foreign gases are permitted to flow through the valves 52 or 55 into the coil 54, bearing 120 with them their content of gaseous refrigerant, they are exposed to a temperature within the regenerator casing 46 which is considerably lower than the condensing 125 point of the gaseous refrigerant at the par- 130

ticular pressure existing inside the coil, which latter is thereby liquefied and flows downward and is drained off through the valve 55 into the receiver 21. It will be noted that the pipes 53 and 20 and the receiver 21 are maintained at substantially the same pressure during this operation, and the gases in the receiver may flow upward into the regenerator coil 54 and then be likewise separated. As the plant continues to work, the foreign gases which are not condensed will accumulate in the coil 54 and especially in the upper part thereof. From time to time the foreign gases are slowly drawn off through the pipe 56 by slightly opening valve 55 during which operation very little, if any, refrigerant will escape.

On the other hand, the oil within the casing 46 of the regenerator delivers its refrigerant in a gaseous condition as set forth above, and settles to the bottom of the casing 46. From time to time, as the oil accumulates within this casing, the oil feeding valve 45^a which delivers oil to the casing 46 may be closed and the outlet valve 59 opened, so that the oil is permitted to pass through the pipe 60 to an oil storage receptacle from which it may be removed and disposed of or if in suitable condition retained for further use in the compressor, or other portions of the plant.

By this method of operating and the apparatus for accomplishing it, the refrigerant contained in the foreign non-condensable gases is recovered by the utilization of the admixture of refrigerant contained in the trapped oil, so that there is substantially no loss of refrigerant from the system as a whole, and the foreign non-condensable gases and the oil are each separated in a relatively pure condition, without the expenditure of external energy for heating or cooling the same.

It is obvious that the invention is not limited to the specific apparatus or to any specific method of employment but that these may be modified within the scope of the appended claims.

What is claimed as new is:

50. 1. In a refrigerating plant, a compressor, a condenser, an expansion valve, a refrigerating coil, conduits connecting said elements, oil traps disposed between said condenser and said refrigerating coil, a regenerator casing in communication with said oil traps to receive oil therefrom, a gas suction pipe communicating between said casing and the intake of said compressor, a condensing coil in said casing and in communication with the outlet from said condenser, a gas purging line from said condenser to said condensing coil, and a foul gas purging valve to relieve foul gases from said coil.
  55. 2. In a refrigerating plant, a compressor, a condenser connected with said compres-
- sor, a high pressure oil trap in said connection, a gravity liquid line from said condenser, a liquid receiver connected to said gravity line, a liquid line from said receiver, an expansion valve in said liquid line, a refrigerating coil connection to said liquid line beyond said expansion valve, a main suction line from said refrigerating coil to said compressor, an oil drum in communication with the bottom of said receiver, an oil trap and drain at the inlet to said refrigerating coil, a regenerator casing, conduits communicating between said oil traps and drum and said casing, at the lower end of said casing a valve for the removal of the oil remaining after regeneration, a regenerator suction line from said casing to said main suction line, a gas pressure equalizing and purging pipe communicating between the outlet end of said condenser and the top of said receiver, a vertical condensing coil in said casing in communication with said equalizing pipe at its lower end, and a foul gas withdrawal pipe and valve in communication with said coil at its upper end.

3. A purging regenerator for a refrigerating plant comprising a casing adapted to receive oil mixed with refrigerant from said plant, a vertical coil in said casing, a gas conduit from the outlet of the condenser of the plant to the lower end of said coil, a combined gas and gravity conduit from the receiver of the plant to the lower end of said coil, a suction conduit from the upper end of said casing to the compressor of the plant, an oil withdrawal pipe at the bottom of said casing, and a foul gas purging connection at the upper end of said coil.

4. In a refrigerating plant having a compressor-condenser-expander circuit, means for partially separating oil from refrigerant by gravity, a heat-exchange vessel having a high pressure and a low pressure compartment, a conduit to bring the partially separated oil into the low pressure compartment, means for partially separating foul gas from refrigerant, a conduit to bring the partially separated foul gas into the high pressure compartment, whereby the exchange of heat between such partially separated oil and foul gas will effect a separation of refrigerant therefrom, means to return the separated refrigerant into the circuit, and means for collecting and removing the oil and foul gas.

5. The method of purging a refrigerating plant of oil and foul gas, which consists in partially separating the oil in the high pressure portion of the plant from the refrigerant, reducing the pressure upon the partially separated mixture of oil and refrigerant whereby to evaporate a portion of the refrigerant contained therein, partially separating the foul gas from the refrigerant in the high pressure portion of the plant, effecting

- a heat exchange between the two mixtures whereby to cool the refrigerant contained in the foul gas mixture to liquefy the same and to heat the refrigerant contained in the oil mixture whereby to volatilize the same, returning the volatilized refrigerant into the system at the low pressure side, and returning the liquefied refrigerant into the system at the high pressure side.
- 10 6. The method of purging a refrigerating plant of oil, which consists in partially separating the oil from the refrigerant in the high pressure portion of the plant, reducing the pressure upon the partially separated mixture whereby to evaporate a portion of the refrigerant contained therein, separating the foul gases from the high pressure portion of the plant, and effecting a heat ex-
- change between the foul gases and the mixture to evaporate the residuum of refrigerant therefrom.
7. The method of purging a refrigerating plant of foul gases which consists in partially separating the foul gases from the high pressure portion of the plant, separating oil from the plant, bringing the separated oil at low pressure into heat exchanging relation with the partially separated mixture of foul gas and refrigerant whereby to liquefy the refrigerant therein, returning the refrigerant for circulation in the plant, and removing the foul gases therefrom.

In testimony whereof, I affix my signature.

NORMAN H. GAY.
